CLAIM

The ornamental design for a video game controller for use with an exercise apparatus, as shown and described.

DESCRIPTION

FIG. 1 is a front perspective view of my video game controller for use with an exercise apparatus, showing a typical embodiment of my new design;
 FIG. 2 is a front end elevational view of my video game controller for use with an exercise apparatus;
 FIG. 3 is a rear end elevational view of my video game controller for use with an exercise apparatus;
 FIG. 4 is a left side elevational view of my video game controller for use with an exercise apparatus, which is a mirror image of its right side elevational view;
 FIG. 5 is a top plan view of my video game controller for use with an exercise apparatus; and,
 FIG. 6 is a bottom plan view of my video game controller for use with an exercise apparatus.

UNITED STATES PATENT AND TRADEMARK OFFICE
CERTIFICATE OF CORRECTION

PATENT NO. : Des. 375,531

DATED : November 12, 1996

INVENTOR(S) : Steven C. Visser

It is certified that error appears in the above-identified patent and that said Letters Patent is hereby corrected as shown below:

In DESCRIPTION at FIG. 5, please replace "appatatus" with
--apparatus--.

Signed and Sealed this
Fourth Day of March, 1997
